CLAIM

The ornamental design for a lavatory, as shown and described.

DESCRIPTION

In a preferred embodiment, the nature of this product is as a plumbing fixture in the form of a lavatory which is primarily useful for washing various items and the body parts of humans.

FIG. 1 is a left, top, front perspective view of a lavatory embodying my new design;

FIG. 2 is a top plan view thereof;

FIG. 3 is a front elevational view thereof, the rear elevational view thereof being a mirror image of the front shown;

FIG. 4 is a left side elevational view thereof, the right side elevational view thereof being a mirror image of the left side shown;

FIG. 5 is a bottom plan view thereof; and,

FIG. 6 is a sectional view taken along line 6—6 of FIG. 2.

The broken line representations in the figures are for the purpose of illustration only, and form no part of the claimed design.
